APPARATUS FOR UNDULATING RODS

Renn Zaphiropoulos, Oakland, Calif., assignor to Chromatic Television Laboratories, Inc., New York, N. Y., a corporation of California

Application September 15, 1953, Serial No. 380,311

7 Claims. (Cl. 49—7)

The present invention relates to vibrational damping rods of zigzag character. Such damping rods find application in, for example, grid structures employing substantially parallelly arranged and tautly strung conductors normally occupying a common plane. Grid structures of this character may be employed as operative components in cathode-ray tubes utilized for the reproduction of color television. The grid structures comprise 400 to 500 or more small diameter, tautly drawn wire conductors. Any random disturbance may readily cause the grid wires to vibrate at the natural period of the structure. Likewise, electrical stresses established when operating potentials are applied to certain strands of the grid structure relative to other strands thereof may occasion vibrational tendencies.

It is a purpose of this invention to provide apparatus for undulating rods which can be interleaved among the strands of the grid structure to provide vibrational damping. The elongated rods to be made into damp rods are undulated through the application of force or pressure effective at generally uniformly spaced positions therealong, with successive positions of pressure application being from opposite directions. The rods may comprise vitreous material having suitable insulating characteristics as not to interfere with the electrical functions of the grid structure. The pressure application is maintained while the rod is softened or plasticized which causes it to assume a generally zigzag configuration in accordance with the pressure applied. The assumed shape is preserved while the rod is hardened. Generally, the rod is softened through the application of heat effective throughout its length or differentially effective in a progressive manner along the length thereof as disclosed in United States patent application Serial No. 380,205 concurrently filed by the same inventor and entitled "Method of Undulating Rods for Electrode Structures." The said application has now issued as U. S. Letters Patent No. 2,778,161 granted January 22, 1957.

The application of pressure at spaced intervals along the length of the rod is conveniently accomplished through the employment of a pair of cooperating sets of generally uniformly spaced and substantially rigid elements. The rigid elements may comprise a series of tautly drawn strands disposed in grill-like manner. The strands comprising one grill occupy positions substantially intermediate the strands of the other grill when they are closed. The grills are adapted to be opened to receive a rod which is disposed substantially normal to the plates or strands. The grills are then closed to interleave the plates or strands thereof and apply pressure to the rod at spaced positions therealong. The closed position is maintained while the rod is softened, preferably by heating, permitting the strands to come into a common plane while zigzagging or undulating the clamped rod. The heat is then removed or at least reduced to such an extent that the rod is permitted to harden in its distorted condition to comprise an undulated damp rod. Damp rods in accordance with the foregoing

2

are placed in the electrical grid structure in spaced relation to prevent or at least damp vibrations.

In order that the damp rods may be mass produced, a length of stock material, such as insulating vitreous material corresponding to a dozen or more damp rod lengths is undulated and then cut into suitable lengths. A supply of the damp rod material may be stored upon a large rotatable drum which is driven in synchronism with a cutter mechanism interposed between the drum and a cradle adapted to receive the multiple length damp rod stock to be undulated. The cradle is disposed above a grill so that subsequent to the cutting operation, it may be tilted to place the multiple length damp rod stock in position on the grill for the clamping operation. A mechanism is provided to close a second grill over the damp rod stock thereby affording pressure application at spaced intervals therealong. The damp rod stock is then softened by the application of heat developed by a filament or heater disposed in proximity therewith to enable the elements of the grills to assume a coplanar relation in undulating the damp rod stock. Next, the upper grill is opened to permit the multiple length undulated damp rod to be moved off to the lower grill, and discharged along a guideway or to a conveyor for sectionalizing into damp rods of required or normal length. The entire operation is synchronized through a common driveshaft requiring only a single source of power.

Accordingly, among the objects of the present invention are the following: the provision of automatically operable apparatus for undulating rods; and the provision of apparatus for mass producing zigzag damp rods.

The present invention will further be described with reference to the accompanying drawing wherein:

Fig. 1 is a view in side elevation of apparatus in accordance with the present invention;

Fig. 2 is a view in plan of the structure of Fig. 1 as seen along a plane marked 2—2 of that figure;

Fig. 3 is a view in end elevation of the structure of Fig. 1, the plane of section being indicated by the line marked 3—3;

Fig. 4 is a cross sectional view of a pair of hinged grills in open position;

Fig. 5 is a view of the grills of Fig. 4 in closed or operative relation;

Fig. 6 is an isometric view of a portion of the grills of Figs. 4 and 5;

Fig. 7 is a view in elevation of a heater in proximity with damp rod stock being undulated;

Fig. 8 is a detailed isometric showing of a portion of the cradle and guiding fingers of the structure of Fig. 1;

Fig. 9 is a view in elevation of the cradle and guiding means and operating mechanism therefor;

Fig. 10 is a view in end elevation of the grills and operating mechanism therefor;

Fig. 11 shows in elevation a suitable cutting mechanism and operating mechanism therefor;

Fig. 12 is a view in elevation of mechanism for controlling the position of the heater;

Fig. 12a shows in side elevation a suitable cam and follower arrangement for positioning the heater;

Fig. 13 is a schematic showing on enlarged scale of the relationship maintained between the strands held by the grills, as shown by Figs. 4 and 5, with respect to the damp rod stock at the time of initiating the undulating operation; and

Fig. 13a is a schematic representation of the coplanar relationship achieved by the strands following undulation of the damp rod stock and exemplifies also the relative shaping of the damp rod stock with respect to the coplanarly positioned strands.

Referring now to the drawings and particularly to the first three figures, a complete machine is shown for fabri-

cating a multiple length damp rod. A rectangular frame 21 is provided to support the various components comprising the undulating apparatus. A large drum 23 contains a supply of the damp rod material 25 which is fed through a pair of felt rollers 27 and along a fixed open chute 29 to a rotatable cradle 31. The damp rod stock 25 is preferably vitreous strand material having a diameter ranging in the neighborhood of three to six mils depending again upon the size of the grid structure in which the damp rods are to be employed. The vitreous material is pushed onto the cradle 31 by the drum 23 and cut to a length generally conforming to that of the cradle by a flame cutter 33.

The cradle is best shown in Fig. 8 which reveals its arcuate shape. The length of the cradle is dependent of course upon the number of individual damp rods which are to be cut from the multiple damp rod stock operated upon. At spaced intervals along the length of the cradle there is provided a plurality of fingers or guides 35. The upper reach of each guide is spaced sufficiently above the cradle to permit the damp rod stock 25 to pass therebeneath. The cradle 31 is pivotally supported from the frame 21 on the pins 37 for partial rotation to slide the damp rod stock 25 along the guides 35 onto a lower grill 39 which is preferably fixed in position. An upper grill 41 is hinged to the lower grill 39 along the pivot axis 43 (Figs. 4 and 5).

The grills are shown constructed of taut strands 45 arranged over spacer bars 47. A continuous length of wire is stretched back and forth between the spacer bars 47 of each grill to provide the parallelly arranged strands 45. A rectangular base 49 is provided with notches 51 (Fig. 6) at spaced intervals along outer edges thereof so that the stringing wire may be passed through a notch 51 and underneath a projection 53 and back out an adjacent notch 51 to provide an anchoring means for the strands. A slotted guide bar 55 is secured to an outside edge of each of the spacer bars 47, as for example by spot welding, to locate the individual strands 45 in spaced apart relation. While the slots 56 of the guide bar 55 are illustrated as substantially uniformly spaced, it is to be understood that the spacing of the slots and hence strands 45 may be graduated to compensate for deviations in the angle of incidence of the electron scanning beam between the tube axis and edges of the target associated with a grid structure employing graduated spacing and correspondingly undulated damp rods.

The strands 45 of the upper grill 41 are adapted to interleave respectively with the strands 45 of the lower grill 39 when the grills are closed through operation of the lever 57. The knife-like edges of the spacer bars 47 insure that the strands 45 occupy a common plane when the grills are closed. However, when the damp rod stock 25 is interposed between the grills, the strands 45 are displaced from the normal common plane (Fig. 5) and exert pressure at spaced intervals along the stock 25 from opposite directions. The upper guide fingers 35 extend slightly beyond the lower guide fingers to pass between the strands 45 and to an ultimate position approximately halfway across the grid 39. Hence the damp rod stock 25 is deposited on the lower grid and then rolled into proper position substantially normal to the strands 45 for clamping.

With the damp rod stock 25 clamped between the grills 39 and 41 it is softened by heat developed by a heater 61. The heater 61 is comprised of a ceramic holder 63 adapted to contain a heater filament 65. The ceramic holder 63 is supported above a frame cross arm 67 by an upriser 69 hinged at 70 to an end thereof (Fig. 7) to permit the filament to be swung into proximity with the clamped damp rod stock for heating and then lowered by the driving mechanism to be explained in detail hereafter. Electrical connection is established to the heater filament 65 through a conventional electric plug 85 and cord 87. An adjustable rheostat 89 is connected between the plug 85 and the filament 65 to provide control over the amount

of current delivered to the filament and hence the heat applied to the damp rod stock 25.

Immediately prior to the initiation of the heating operation, as is also shown at the left of Fig. 7, the strands 45 supported by both the upper and lower grills 41 and 39 are forced out of their normal common plane by the damp rod stock 25, the rod stock being generally straight, as shown by Fig. 13, and the strands 45 being arranged so that alternate strands are on the same side of the rod stock. The displacement between the centers of the strands 45 is then equal to the diameter of the rod stock plus the diameter of the strand. By Fig. 13a the general relationship of the strands 45 to the rod stock 25, as also shown by Fig. 7, is exemplified on an enlarged scale. In Fig. 13a it will be observed that following heating of the rod stock 25 that the strands 45 which have exerted forces against the rod stock from opposite sides cause the rod to undulate as the strands 45 approach the indicated coplanar relationship so that strands at either side of the rod stock finally are positioned (as when the color-control grid is in use) so that their centers are all in the common plane. For this condition it will be observed that the strands have moved downwardly or upwardly, as the case may be, by distances equal to one-half the sum of the strand and damp rod cross sectional dimension, the strand dimension being indicated as d' and the damp rod stock dimension being indicated as d in Fig. 13 showing particularly the relative displacement.

After the damp rod stock 25 has been undulated the grill 41 is opened via lever 57 to permit a blast of air from an exhaust pipe 91 to move the undulated multiple damp rod off of the grill 39 and down the guideway formed by the arms 93 to a cutter (not shown) where the undulated multiple damp rod is sectionalized into individual damp rods.

The driving and control mechanism is operated from a motor 101 which drives a bevel gear 103 through a gear reduction box 105. A drive shaft 107 is driven through the bevelled gear 103 coaxing with a coplanar bevel gear 109 which also transmits motion through a spur gear 111 fixed to a vertical driving shaft 113. The vertical shaft 113 turns the drum 23 to unwind vitreous supply material therefrom through a pair of gears 115 and 117. The angular speed of the drum 23 is correlated with the other operations so that a suitable stock length of vitreous material 25 is placed on the cradle 31 during the time in which the previous stock is being undulated. After such a length has been unreeled onto the cradle 31 the flame cutter 33 rises to the position shown in Fig. 1 to cut the vitreous material. This is accomplished through a spring-loaded follower 121 which is urged against a cam 123 fixed on the drive shaft 107. The spring is not shown as such follower arrangements are well known. The follower 121 is adapted for vertical motion through the sleeve 125. Its upper extremity is connected to a lever arm 125 which supports the flame cutter 33 and which pivots about a fixed axis 127. The flame cutter is normally in the position shown in dotted outline in Fig. 11 and is only raised to the cutting position once for each revolution of the drive shaft 107. The cam 123 is oriented on the drive shaft 107 such that the flame cutter is raised to its operative or cutting position after the continuously driven drum has unreeled the required amount of vitreous stock. The flame type cutter requires only a split second to cut the 3 mil glass rod and accomplishes the cutting function without disturbing the position of the damp rod stock 25. However, other known types of cutters may be used without departing from the spirit of the invention.

The next step in the overall operation is that of depositing the length of stock retained by the cradle 31 onto the fixed grill 39. This is accomplished by a second cam 131 also fixed to the common drive shaft 107. A vertical follower 133 is guided by the sleeve 134 and spring loaded to bear against the cam 131. The follower 133 is loosely coupled to a lever 135 which extends to

one of the pins 37 set in the back edge of the cradle 31. The cam 131 permits the cradle normally to occupy a substantially horizontal position and to be tilted into the position shown in dotted outline in Fig. 9 once for each revolution of the common driveshaft 107. This enables the damp rod stock to slide down the guide fingers 35 and into position on the fixed grill 39.

The upper grill 41 must occupy its upper or open position to permit the damp rod stock to be properly located by the guide fingers 35. This is accomplished by a further cam 141 fixed to the common drive shaft 107. The lever 57 which pivots the upper grill 41 about the fixed axis 43 is connected to a follower 143 which is spring urged against the cam 141 and which is confined to vertical movement by the sleeve 145. The spring (not shown) in this instance is of the heavy duty type to accommodate the weight of the grill 41. Heating of the damp rod stock 25 is accomplished when the ceramic holder 63 is in the position shown in Fig. 7 or as shown in dotted outline in Fig. 12. A cam 151 shown in side elevation in Fig. 12a is fixed to the common drive shaft 107 (Fig. 1) to drive a follower 153 adapted for vertical movement through the sleeve 155 secured to the cross arm 67. The upper extremity of the follower 153 fits an indentation in the lower surface of a lever 157 which pivots about a fixed point 159 provided by a support 161. The other end of the lever 157 is coupled to a stub 163 depending from the ceramic holder 63 by a pin 165 which extends through a slot 167 oriented longitudinally of the lever 157. The ceramic holder 63 is moved into its upper or heating position once during each cycle, as will be seen from a comparison of the cams of Figs. 9 through 12. This occurs shortly after the grill 41 is closed. Heating requires only a short interval of the cycle and consequently the ceramic holder 63 is quickly lowered by gravity allowing time for cooling (which occurs almost instantaneously) during the interval of closure of the grills. The actual spacing between the heater filament 65 and the damp rock stock 25 may be of the order of $\frac{3}{32}$ " which is represented in Fig. 7 in a slightly exaggerated showing.

The cam 141 is indented over a sufficiently large portion of its periphery to permit the grill 41 to remain in its open position long enough for a previously undulated multiple damp rod to be removed and a damp rod stock to be placed thereon for subsequent undulation. The blast of air from the exhaust pipe 91 which removes a multiple damp rod from the grill 39 is controlled by a solenoid air valve 171 (Fig. 1) operated by a fixed microswitch 173. The microswitch 173 is fixed to the frame 21 by a support 175 in the position shown in Fig. 10 such that the base 49 of the upper grill 41 depresses the plunger 177 when the grill is in its fully open position. The microswitch 173 actuates solenoid valve 171 to open the air supply which passes through hose 179 and exhausts out pipe 91. The plunger 177 is released when the grill 41 starts to close thus closing off the air while still permitting time for the deposition of the vitreous stock because of the gradual contour of the cam 141 and sharp contour of the cam 131.

The entire foregoing action is accomplished during a single cycle of operation which may require a full minute. The drive shaft 107 and cams 123, 131, 141 and 151 turn one complete revolution each cycle. The cams are oriented on the common drive shaft 107 in the positions shown in Figs. 9 through 12a. The opening and closing of the grill 41 requires approximately 135° revolution of the drive shaft 107 allowing 225° for heating, undulating and cooling. The rheostat 89 permits the current through the filament 65 to be adjusted so that heating may be accomplished quickly allowing ample time for sufficient cooling of the small diameter vitreous rod prior to discharge.

What is claimed is:

1. Apparatus for undulating an elongated rod com-

prising in combination, a first plurality of spaced substantially taut strands defining at least a common plane, a second plurality of spaced substantially taut strands also defining at least a common plane, means for positioning the rod on the first plurality and substantially normal to the strands thereof, means for closing the second plurality over the rod with the strands of the second plurality interleaving with the strands of the first plurality to apply pressure against the rod at spaced positions therealong, means for heating the so-clamped rod to permit the strands to undulate it in assuming substantially coplanar relation, and means for relieving the heat with the strands in coplanar relation to insure permanent deformation of the rod.

15 2. Apparatus for undulating an elongated rod comprising, in combination, a pair of cooperating sets of spaced and substantially rigid elements, means for positioning the rod between the sets and substantially normal to the elements thereof, means for closing the sets to interleave the elements thereof and apply pressure to the rod, means for introducing heat to the rod while under pressure to permit the elements to undulate it in assuming substantially coplanar relation, and means for relieving the heat with the sets of elements closed to insure permanent deformation of the rod.

20 3. Apparatus for undulating a vitreous rod comprising, in combination, a pair of cooperating grills each including an open frame and a plurality of taut strands disposed thereacross in spaced relation, the strands of one of the grills being adapted for location respectively between the strands of the other of the grills when the latter are closed, means for cyclically opening and closing the grills, means for locating the vitreous rod between the grills when open and substantially normal to the strands thereof so that closure of the grills over the vitreous rod applies pressure thereto through the taut strands, means for introducing heat to the vitreous rod while under pressure to permit the strands to undulate it in assuming substantially coplanar relation, and means for discharging the undulated vitreous rod when the grills are open.

25 4. Apparatus for undulating a vitreous rod comprising, in combination, a pair of cooperating grills each including a plurality of generally uniformly spaced and substantially taut strands, means for cyclically closing the grills to interleave respectively the strands thereof in a common plane, means for positioning the vitreous rod between the grills substantially normal to the elements thereof such that adjacent strands apply pressure thereto from opposite directions, means for introducing heat to the vitreous rod while under pressure to permit the strands to undulate it in assuming substantially coplanar relation, and means for relieving the heat with the grills closed to insure permanent deformation of the rod.

30 5. Apparatus for undulating elongated vitreous rod material comprising, in combination, a pair of cooperating grills each including an open frame and a plurality of taut strands disposed thereacross in spaced relation, means for cyclically closing the grills respectively to interleave the strands thereof in a common plane, means for cutting the vitreous rod to lengths of substantially the extent of the plurality of strands, means for locating the cut vitreous rod between the grills and substantially normal to the strands thereof so that upon closure of the grills pressure is applied against the rod from opposite directions by the strands of the respective grills, means for introducing heat to the vitreous rod while under pressure to permit undulation thereof by the strands in assuming substantially coplanar relation, and means for discharging the undulated vitreous rod when the grills are open.

35 6. Apparatus for undulating vitreous rods comprising, in combination, a pair of hinged grills adapted to be opened and closed, each of the grills including an open frame and a plurality of taut strands disposed thereacross in spaced relation, the strands of one of the grills inter-

leaving in a common plane with the strands of the other of the grills when the latter are closed, cyclically operable means for locating a vitreous rod between the open grills and substantially normal to strands thereof, means for cyclically closing the grills to apply pressure to the rod at spaced positions therealong and subsequently opening the grills, means for introducing heat to the vitreous rod while under pressure to permit undulation thereof by the strands in assuming substantially coplanar relation, means for removing the heat from the vitreous rod while the grills are closed to insure permanent deformation thereof, and means for discharging the undulated vitreous rod. 10

7. Apparatus for undulating elongated vitreous rods comprising, in combination, a first set of generally uniformly spaced and substantially taut strands, a second set of generally uniformly spaced and substantially taut strands, hinge means connecting the first and second set of strands to permit the strands to be closed into interleaved and coplanar relation, means for positioning a 20

vitreous rod between the sets and substantially normal to the strands thereof, means cyclically operative for closing the sets to apply pressure to the vitreous rod and subsequently open the sets, means for introducing heat to the vitreous rod while under pressure to permit undulation thereof by the strands assuming substantially coplanar relation, means for relieving the heat with the sets of strands closed to insure permanent deformation of the rod, and means effective to discharge the deformed rod from the open sets. 10
